UNITED STATES PATENT OFFICE.

WILLIAM T. HORMES, OF GOVANS, MARYLAND, ASSIGNOR TO SOLOMON HIMMEL, OF BALTIMORE, MARYLAND.

DISPLAY-RACK.

1,283,518.

Specification of Letters Patent.

Patented Nov. 5, 1918.

Application filed April 9, 1915. Serial No. 20,268.

To all whom it may concern:

Be it known that I, WILLIAM T. HORMES, a citizen of the United States, residing at Govans, in the county of Baltimore and 5 State of Maryland, have invented new and useful Improvements in Display-Racks, of which the following is a specification.

This invention is a device for displaying or exhibiting goods, and relates to that type 10 of display devices wherein a rotatable rack is employed for supporting the goods to be displayed, and normally inclosed within a case or compartment. Such cases or compartments are usually constructed with glass 15 walls or panels, so that the goods on display may be readily seen by the prospective customers passing the same, and at the same time be protected from dust and promiscuous handling. When it is desired to more closely 20 inspect the article upon display, the rack is rotated to permit of the desired examination and selection. In view of the fact that economy of floor space demands that the area occupied by the case be as small as 25 possible, it is usually customary to construct the case of oblong shape, with the rack or supporting member conforming to this shape, being of a length greater than the width of the case. To provide the necessary 30 clearance for its rotation, the rack is so mounted as to be moved to a point near the front of the case, a sufficient distance to permit the ends of the rack to swing in front of the rear wall or panel of the case, when 35 the rack is rotated. Heretofore, display racks of this type have been usually employed for the storing and display of ready made garments, such as men's and boys' clothing, women's dresses, and the like. One 40 of the objects of the invention is to broaden the field of usefulness of such display racks, by providing simple and efficient means whereby smaller articles of merchandise, such as millinery and millinery findings in- 45 cluding plumes, trimmings, and the like, may be stored and exhibited, and yet be easy of access when removal or close examination is desired. A further object is to provide improved means for removably supporting 50 boxes or similar receptacles, provided with glass covers, upon a rotatable support, in such manner as to admit of ready access to the contents thereof.

The invention will be hereinafter fully

set forth and particularly pointed out in the 55 claims.

In the accompanying drawings:—

Figure 1 is a front elevation of a display rack constructed in accordance with the invention. Fig. 2 is a transverse sectional view 60 of the case, illustrating the rack in end elevation. Fig. 3 is an enlarged detail view illustrating the means for attaching the receptacles to the rack. Fig. 4 is a detail view illustrating the carriage for supporting the 65 rack. Fig. 5 is a detail view of the device for controlling rotation of the rack.

Referring to the drawings, 10 designates a case of any suitable or preferred structure, the bottom of which is provided with a 70 channel 11. Located on opposite sides of said channel, and parallel with the walls thereof, are guides 12, between which a carriage 13 is mounted to reciprocate. Said carriage is provided with a tubular boss 14 75 which rotatably supports a shaft 15. The lower end of the shaft 15 projects below the carriage and is provided with a cross head 16, having rollers 17, mounted to run between guides 18, which are united at their 80 outer ends by a circular portion 19. The construction is such that when the carriage is moved inwardly, the rollers 17 are caused to enter the space between the straight portions of the guides 18, so that rotation of the 85 shaft is prevented. When the carriage is moved to the forward or outer position, the rollers 17 engage the circular portion 19, thereby permitting the shaft to rotate. The foregoing arrangement is described merely 90 for the purposes of illustration, and it is not intended to limit the invention thereto, as any of the other well known forms of reciprocating carriages and locking and unlocking devices, may be employed without 95 departing from the spirit of the invention.

Rigidly attached to the shaft 15, are brackets 20, spaced one from the other, each bracket being provided with oppositely disposed arms 21, terminating in widened seats 100 22, for the boxes or receptacles 23. Said boxes rest upon the seats 22 and are retained in position by means of clamps each formed of a member 24 having an overhanging angular portion 25, adapted to fit over the top 105 of the box or receptacle, the said members 24 being provided with lugs 26, having openings therein, the opening of each lug being

threaded to engage a correspondingly threaded portion of an adjusting rod 27, said rods being passed through tubular bosses with which the arms 21 are provided. Said adjusting member is provided with a head 28, adapted to bear against the underside of the arm 21, in such manner that when the angular portion 25 is engaged with the top of a box or receptacle, a clamping pressure sufficient to retain it in position, is obtained by screwing up the adjusting member 27, said head being shaped to be conveniently grasped. The boxes or receptacles 23 may be provided with removable or hinged covers 29, preferably of glass, so as to display the contents of the receptacles, and permit of ready removal thereof.

From the foregoing it will be seen that the invention provides simple and efficient means for removably supporting the boxes or receptacles in a most convenient manner for effective display of the articles contained therein, and yet insure perfect protection of such articles from being soiled by dust or promiscuous handling. Should it be necessary or desirable to remove any one of the boxes or receptacles, the removal may be readily accomplished by loosening and disengaging the clamp which retains it in position, and a new box may be substituted and as readily secured in position by again tightening up the clamp. By supporting the boxes upon the shaft 15, and carriage 13, the rack may be quickly and easily manipulated to present all of the boxes to view for inspection. By locking the clamping members independent of the arms 21, the receptacle 23 may be rigidly secured in position and yet ample clearance be provided between the top of the receptacle and any of the arms 21 which may overhang the same.

Having thus explained the nature of my invention and described an operative manner of constructing and using the same, although without attempting to set forth all of the forms in which it may be made, or all of the forms of its use, what I claim is:—

1. The combination with a case or cabinet, of a rotatable shaft mounted to reciprocate to and from a position within said case or cabinet, a plurality of spaced apart brackets attached to said shaft, each bracket being provided with a support having an opening therethrough, adjusting rods passed through the openings of the respective supports, each adjusting rod having a

shoulder bearing against one surface of the support through which it is passed, and clamp members adjustably engaged by the adjusting rods and coöperating with the respective supports to clamp articles between them. 60

2. The combination with a case or cabinet, of a rotatable shaft mounted to reciprocate to and from a position within said case or cabinet, a plurality of spaced apart brackets attached to said shaft, each bracket being provided with a support having an opening therethrough, adjusting rods passed through the openings of the respective supports, each 70 adjusting rod having a shoulder bearing against one surface of the support through which it is passed, and clamping members each having an overhanging portion and a depending internally threaded lug, said adjusting rods being threaded to engage the lugs of the respective clamp members. 75

3. The combination with a case or cabinet, of a rotatable shaft mounted to reciprocate to and from a position within said case or cabinet, a plurality of spaced apart brackets attached to said shaft, each bracket being provided with oppositely extended arms terminating in elongated and widened seats, each arm having an opening therethrough, 80 adjusting rods passing through the openings of the respective arms, each adjusting rod having a shoulder bearing against one surface of the arm through which it is passed, and clamp members adjustably engaged by 85 the adjusting rods and coöperating with the respective supports to clamp the articles between them. 90

4. An improved display rack comprising a rotatable shaft, a plurality of spaced apart 95 brackets attached to said shaft, each bracket being provided with a support at its extremity, and means associated with the support and overhanging the same for clamping articles thereupon in position to permit 100 clearance between said articles and any supports which may overhang the same, the clamping means of each support being independent of the other supports. 105

In testimony whereof I have hereunto set my hand in presence of two subscribing witnesses.

WILLIAM T. HORMES.
